US00D868326S

(12) **United States Design Patent** (10) Patent No.: **US D868,326 S**
Griffin et al. (45) Date of Patent: ** Nov. 26, 2019

(54) **COMBINATION ILLUMINATION DEVICE AND POWER SYSTEM**

(71) Applicant: **Charge Ahead LLC**, Florence, MA (US)

(72) Inventors: **Anne Marie Griffin**, Florence, MA (US); **Stephen Joseph Smith**, Yonkers, NY (US)

(73) Assignee: **CHARGE AHEAD LLC**, Florence, MA (US)

(**) Term: **15 Years**

(21) Appl. No.: **29/648,976**

(22) Filed: **May 25, 2018**

Related U.S. Application Data

(60) Division of application No. 29/562,834, filed on Apr. 29, 2016, now Pat. No. Des. 842,518, which is a continuation-in-part of application No. 29/507,827, filed on Oct. 31, 2014, now abandoned, and a continuation-in-part of application No. 29/507,837, filed on Oct. 31, 2014, now abandoned.

(57) **CLAIM**

The ornamental design for a combination illumination device and power system, as shown and described.

DESCRIPTION

FIG. 1 is a perspective view of the top, front, and right side of a combination illumination device and power system showing an embodiment of the new design.

FIG. 2 is a front view thereof.

FIG. 3 is a back view thereof.

FIG. 4 is a left view thereof.

FIG. 5 is a right view thereof.

FIG. 6 is a top view thereof; and,

FIG. 7 is a bottom view thereof.

1 Claim, 7 Drawing Sheets
